UNITED STATES PATENT OFFICE.

GILLAM D. GODWIN, OF WADE, NORTH CAROLINA.

FOLDING COOP.

1,259,848.

Specification of Letters Patent. Patented Mar. 19, 1918.

Application filed April 14, 1917. Serial No. 161,979.

To all whom it may concern:

Be it known that I, GILLAM D. GODWIN, a citizen of the United States, residing at Wade, in the county of Cumberland and 5 State of North Carolina, have invented certain new and useful Improvements in Folding Coops, of which the following is a specification.

My invention relates to a new and useful 10 improvement in crates or coops and especially to a folding coop that is used for shipping chickens, ducks or other fowls.

An object of my invention is to provide a 15 coop that may be folded when empty so as to take up a minimum amount of space.

Still another object of my invention is to provide a coop wherein the same may be quickly and readily opened or put in its set up position.

20 Also, after having manually forced the sides tightly against the ends, by tightening one screw at each end of the coop the top will be drawn toward the bottom so that when the coop is in its open or final position, 25 the entire structure will be held firmly and strongly together.

Still another object of my invention is to so provide the ends that water may quickly drain off with any refuse when the crate is 30 washed.

Still another object of my invention is to provide a fastening means that is exceedingly simple wherein after all of the parts of the crate are drawn together, the locking 35 means will firmly hold the said parts in their fixed position.

Still another object of my invention is to provide a crate that will be relatively cheap to manufacture, easy to construct, taking up 40 a relatively small space when folded and having but few parts for locking the crate when in its open position.

With these and other objects in view my invention consists in certain new and novel 45 arrangements and combinations of parts as will be hereinafter more fully described and pointed out in the claim.

In the drawings,

Figure 1 is a perspective view of the coop 50 in its open or set up position.

Fig. 2 is an elevation in the same position.

Fig. 3 is a similar view, but the coop in this instance is in its folded or closed position.

55 Fig. 4 is a top plan view of the coop in its open or set up position.

Fig. 5 is a longitudinal sectional view on line 5—5 of Fig. 4.

Fig. 6 is a detail sectional view on an enlarged scale, and

Fig. 7 is a transverse sectional view through a portion of the coop.

Referring now to the drawings it will be seen that the folding coop comprises a bottom 1, which is shown as rectangular and to 65 which are fastened the side strips 2 and 3 which, as shown, extend for a relatively short distance from the bottom. To these side strips 2 and 3 are fastened the side walls 4 which are hinged preferably on their inner 70 surface, and the said walls are designed to fold inwardly. On the inner side near the top of these side walls are hinged the two halves of the top 5, the position of the hinges being such that these top portions are flush 75 with the upper edges of the side walls.

Secured at the opposite ends of the bottom 1 are the two folding end walls 6 which are also hinged to fold inwardly and rest on the bottom portion 1. The height of the side 80 strips 2 and 3 is such that when the top portions 5 are folded downwardly on the side walls 4 and the side walls 4 folded inwardly, they may rest snugly on the upper surface of the end walls 6 and be supported thereby 85 so that there is no strain on the hinges that fasten the side walls to the side strips.

So far the coop might be considered a conventional one.

It is to be noticed however that the end 90 walls 6 have cut out portions in their lower surface at their ends 7, so that when these end walls are in their upright position the whole lower surface of the end wall is not in contact with the upper surface of the bottom 1, but simply a central portion thereof, so that any water that is thrown or directed 95 into the coop may easily run out of these cut out portions 7, at each end of the coop. In other words the coop may be easily 100 washed or drained and even while in transportation the water cannot collect in the bottom but will immediately run off as desired.

I have also shown reinforcing strips 8 extending across the bottom on its under surface.

Referring now to the locking means which forms a very important part of my invention and which is shown in detail in Fig. 6, it will be seen that a metal strap 9 is pivotally secured to the under surface of one end 110 of the top portion 5 by a screw 10 or any

other desirable means, and the said strap 9 extends over and slightly beyond the edge of the other top portion 5. Secured directly opposite the pivotal end of the strap 9 is a 5 threaded socket 11 for the reception of a screw 12, which is movably secured in a bearing 12^a near the center in the end wall 6. It might be mentioned that as these 10 fastening means are identical in each end portion 6, a description of the one will be a description of the other.

This screw has a knurled head 13 at its lower end and a stop 14 near the center thereof, so that the same, when out of engagement with the threads in the upper 15 socket 11, cannot in any way become lost or jarred from out of its position in the end wall 6. The strap 9 is provided with an opening 15 so that the screw 12 may pass 20 therethrough.

By locking means of this type which may be clearly understood from Figs. 2 and 6, it will be seen that after the coop is opened up, that is the side walls are raised and the top 25 portions opened out and the end walls lifted to their vertical position, the strap 9 is swung so that the opening 15 will come directly under the opening in the socket 11 and the screw 12 is then pushed upwardly 30 through the said opening 15, and screwed into threaded engagement with the socket 11. The opening 15 in the said strap will be so placed that before it comes in alignment with the opening of the socket 11, it 35 will be necessary to force the side walls of the crate together as tightly as possible. This then holds the side walls 4 tightly against the end walls 6 and by tightening up on the knurled head 13, the screw 12 40 being in threaded engagement with the socket 11, the top portions 5 are drawn down tightly against the end walls 6, thereby connecting the bottom 1 and the top portions together. In other words, the whole crate, 45 that is the top and bottom, side and end walls, are held tightly together by forcing

the screw 12 through the opening 15 in the strap 9 and the parts are kept in this position by holding the screw by the thumb nut 13. 50

A door 16 may be formed in the top of the crate and screw eyes or other fastening means correctly located so that the door may be kept in a fastened position when desired.

As the way of setting up the crate has 55 been mentioned it is thought a further description is unnecessary, and to fold the crate it is simply necessary to unscrew the thumb nut 13 which will cause the screw 12 to leave its socket 11 and the strap 9 may 60 then be folded back and the end walls shut down, the top portions folded back on the side portions and the side portions in turn folded inwardly, so that the top portions and side portions will rest on said end walls, 65 which rest on the bottom 1.

If desired lugs or screw eyes or other fastening means may be used as 17, through which a wire may be placed to hold the side walls together when the crate is in its 70 closed position.

From the foregoing it will be seen that the 75 crate or coop is one that is easy to construct, and that by providing a fastening means as hereinbefore described, the coop, when in its set up position, may be firmly secured or in other words, have all its parts tightly drawn together.

Having thus described my invention what I claim as new and desire to secure by Letters Patent is:—

A coop comprising a bottom panel, strips secured to the edges thereof, end panels hinged thereto, side panels hinged to the strips, top panels hinged to the side panels, 60 a strap secured to one of the top panels, a socket member mounted in the other top panel and a screw passing through the end panel and the strap and detachably engaging the socket member. 90

In testimony whereof I affix my signature.
GILLAM D. GODWIN.
